Patented Oct. 26, 1971

222,478

PORTABLE TAPE RECORDER

Raymond A. Massaccesi, Lombard, Ill., and Sheldon Lee Pastor, St. Paul, Minn., assignors to Minnesota Mining and Manufacturing Company, St. Paul, Minn.

Filed June 22, 1970, Ser. No. 23,613

Term of patent 14 years

Int. Cl. D14—01; D3—01
U.S. Cl. D26—14

FIG. 1

FIG. 2

FIG. 4

FIG. 5

FIG. 3

FIG. 6

FIG. 7

FIG. 1 is a perspective view showing the top, front and one side of a portable tape recorder embodying our new design;

FIG. 2 is a top plan view of said portable tape recorder;

FIG. 3 is a bottom plan view of said portable tape recorder;

FIG. 4 is a front elevational view of said portable tape recorder;

FIG. 5 is a rear elevational view of said portable tape recorder;

FIG. 6 is a side view of said portable tape recorder opposite the side appearing in FIG. 1; and

FIG. 7 is a perspective view showing the top, front and one side of said portable tape recorder with the cover removed.

We claim:

The ornamental design for a portable tape recorder, substantially as shown and described.
